CHARLES J. CARLSON AND ALBERT W. LARSON, OF SEATTLE, WASHINGTON.

EXTENSIBLE POLE.

1,415,145.

Specification of Letters Patent. Patented May 9, 1922.

Application filed May 24, 1920. Serial No. 383,614.

To all whom it may concern:

Be it known that we, CHARLES J. CARLSON and ALBERT W. LARSON, citizens of the United States, residing at Seattle, in the county of King and State of Washington, have invented 5 certain new and useful Improvements in Extensible Poles, of which the following is a specification.

This invention relates to extensible rods for 10 use, more particularly, in closets to support clothes hangers.

The object of the present invention is the perfecting of devices of this character.

The invention consists in two complementary 15 rod members connected by bands for relative longitudinal movements and clamping means carried by one of the said bands and engageable with both of the rod members for securing the rod in operative position.

20 The invention in its form now preferred by us is illustrated in the accompanying drawings, in which—

Figure 1 is a front elevational view of the 25 rod shown applied. Fig. 2 is a front elevational view of the same, shown partly in section, with the clamping devices in disengaged positions. Fig. 3 is a view similar to Fig. 2 with the clamping devices shown engaged to the rod members. Fig. 4 is a plan 30 view of Fig. 3.

In carrying out our invention we provide a rod proper consisting of two members 5 and 6 having cylindrical outer end portions 5¹ and 6¹ and semicylindrical inner portions 5² and 6² which are connected by bands 7 and 8.

The band 7 is secured to the rod portion 5² near the extremity of the latter by a brad or screw 9 and is slidable upon the portion 6² of the other rod member.

40 The band 8 is freely slidable upon the rod portion 5² and also upon the rod portion 6² to an extent limited by the movement afforded in a slot 10 of the band 8 to a stud 11 which extends into said slot from the rod 45 portion 6².

Extending from the band 8 beyond the adjacent end of the rod part 6² are ears 12 through apertures of which extends a pin 13. This pin serves as a pivotal support for 50 a substantially U-shaped dog 14 having its lower end serrated to provide teeth 15 which are adapted to engage in the upper surface 16 of the rod part 5². The pin 13 furthermore serves as a fulcrum for a lever 17 having a cam arm 18 adapted to engage against 55

a wearing plate 19 secured to the extremity of the rod part 6² to force the rod members 5 and 6 in opposite directions when the lever is brought from its Fig. 2 position into its Fig. 3 position and subsequent to the dog 14 engaging in the rod part 5². When this occurs the band 8 is held by the dog and the rod member 6 moved within the band and also with respect to the rod member 5. To disengage the dog from the rod member 5 the cam lever is moved from the position in which it is shown in Fig. 3 to that in which it is shown in Fig. 2, resulting in the lever arm 18 engaging the dog to swing the same from its engagement with the rod part 5² and enable the two members to be slidably moved to shorten or extend the effective length of the rod.

To the outer extremities of the rod parts 5¹ and 6¹ are secured bodies 20 of a resilient material, as rubber for example, which prevents the rod from marring the wall surfaces 21 against which the ends of the rod abut. The bodies 20 by being of resilient material yields sufficiently to accommodate the movements of the rod member 6 with respect to the band 8 after the rod has been adjusted in the hands of the operator to extend between the opposite wall surfaces 21. After thus adjusting the rod the operator pushes downward 55 with his finger the dog into engageable position with the rod part 5² and coincidentally effects a relatively small movement to the rod 6 through the medium of the cam lever to temporarily retain the rod in place.

The operator thereupon moves the cam lever into the position in which it is represented in Figs. 1 and 3 whereby the rod is further extended to effect the clamping of the same between the walls.

The rod is readily applied or disconnected and provides a secure and rigid device from which articles may be conveniently suspended.

What we claim is—

In an extensible rod, the combination with a rod-member, a second rod-member connected thereto for relative longitudinal movement, of a band surrounding both of said members, said band being provided with a slot, a stud protruding from the first named member into said slot to limit the longitudinal movement of such member with respect to said band, a dog, a pin pivotally connecting the dog to said band in clamping relation 105

100

105

110

with respect to the second named member, and a cam lever fulcrumed to said pin and engageable with the first named member or with said dogs, selectively, to respectively
5 effect the extension of the rod or the disengagement of the dog from the second named member.

Signed at Seattle, Washington, this 13th day of May, 1920.

CHARLES J. CARLSON.
ALBERT W. LARSON.
